US0D1032645S

(12) **United States Design Patent** (10) Patent No.: **US D1,032,645 S**
Sabourenkov (45) Date of Patent: ** Jun. 25, 2024

(54) **DISPLAY SCREEN WITH GRAPHICAL USER INTERFACE**(71) Applicant: **DoseMe Pty Ltd**, Taringa (AU)(72) Inventor: **Paul Sabourenkov**, Taringa (AU)(73) Assignee: **DoseMe Pty Ltd**, Queensland (AU)(***) Term: **15 Years**(21) Appl. No.: **29/746,708**(22) Filed: **Aug. 17, 2020****Related U.S. Application Data**

(63) Continuation of application No. 29/643,059, filed on Apr. 4, 2018, now Pat. No. Des. 893,524.

(51) LOC (14) Cl. **14-04**

(52) U.S. Cl.

(57) **CLAIM**

The ornamental design for a display screen with graphical user interface, as shown and described.

DESCRIPTION

The FIGURE is a front view of a display screen with graphical user interface showing my new design.

The broken line showing of a graphical user interface is included for the purpose of illustrating portions of the article and forms no part of the claimed design.

1 Claim, 1 Drawing Sheet
